SUCTION OPERATED FAN

Erwin C. Horton, Hamburg, N. Y., assignor to
Trico Products Corporation, Buffalo, N. Y.

Application December 9, 1935, Serial No. 53,624

16 Claims. (Cl. 230—258)

This invention relates to a motor for operating an air circulating fan and particularly to one adapted for use in circulating air in motor vehicles and adjacent windows thereof.

5 Fans of this general type have heretofore been devised, as for example, that disclosed in Patent No. 1,745,114, granted January 28, 1930 to John R. Oishei and Henry Hueber. In fans of this character, and similar accessory-like devices, the construction is of necessity light and simple so as to adapt it as an accessory for motor vehicles. In the fan referred to in the patent above, a blade and rotor or drive are mounted as a unit in a rigid bearing support. Due 10 to their structural fabrication, fans of this general type have heretofore produced a chattering noise by reason of the play in the shaft bearing, among other contributing factors. Such chattering increased as wear in the bearing and 15 shaft occurred, and obviously this became a source of annoyance to the motorist, as well as impaired the efficiency of the fan.

The present invention has for its object to provide a durable fan motor which is quiet and 20 efficient in operation, as well as one wherein the construction facilitates production in large quantities at a minimum expense.

The invention resides in the salient features of construction and their arrangements and combinations of parts as are hereinafter set forth and by which the motor shaft is given a self-adjusting and more or less floating support, reference being had to the accompanying drawing wherein.

35 Fig. 1 is an axial section through the fan motor with parts in elevation;

Fig. 2 is a transverse sectional view through the fan housing or casing;

Fig. 3 is a fragmentary and enlarged sectional view through the impelling jet; and

Fig. 4 is a sectional view of a modified embodiment of the invention.

In proceeding in accordance with the present invention and referring more particularly to the drawing, the motor therein illustrated, by way of example, is of the air or fluid operated type and comprises a housing 1, a driving turbine wheel or rotor 2, a shaft 3, and a blade or propeller 4. The rotor may be fixed to one end 45 of the shaft and the propeller to its opposite end so that these three parts may rotate as a unit. Both the rotor and propeller may be stamped out of light metal, if desired, and one 50 of these elements, preferably the propeller, may be provided with a mounting hub 5 for detach-

able threaded engagement with the shaft 3 to facilitate the assembly of the fan parts, such engagement being secured by a set screw 6.

According to the present invention, the rotor-propeller unit is given what might be termed a 5 floating support in the housing, so as to readily adjust and accommodate itself for most efficient operation. To this end the housing 1 is provided with a journal box or chamber 7 through which the shaft extends for support intermediate the 10 propeller and rotor. One end of this chamber is provided with a transversely extending wall 8 that is formed with an opening 9 slightly larger than the diameter of the shaft, so that the latter is free for restricted movement laterally without 15 chattering against the wall of the opening. The shaft is given self-adjusting and self-aligning journal support at one or more points within this chamber and, according to the present disclosure, such support is afforded by one or more 20 yieldable bearings.

In Fig. 1, the bearings 10 are constructed of yieldable material, such as felt, and contain a quantity of lubricant for greatest efficiency.

Such bearings 10 are constructed and designed 25 to provide a substantial journal bearing for the shaft and are confined in place by ring-like retainers 11 and 12, one or both of which may be free to slide in the chamber 1. To properly support and confine these bearing blocks 10, the 30 opposing or confining side faces of the retainers are oppositely sloped or inclined so that when pressed against the bearing blocks they will serve to urge the blocks inwardly toward the shaft and support the latter free of the retainers, as 35 well as the wall of opening 9. The pressure may be applied automatically, such as by a spring 13, and where the shaft is supported at intervals by spaced bearing blocks so that more than one set of cooperating retainers is required, a single 40 pressure applying spring may be compressed between the adjacent sets of retainers to serve in a dual capacity, as depicted in Fig. 1. The inner 45 end of chamber 1 is shown provided with an in-turned lip 14 to cooperate with the outer end 45 wall 8 and the spring 13 in securing the bearings and retainers in place. This construction affords the desired firmness of support for the shaft and at the same time provides a bearing 50 which is self-aligning and self-adjusting. It further provides for self-lubrication by reason of the spring acting to compress the bearing felts or blocks.

In Fig. 4 the bearing blocks are composite in character and instead of being wholly compress- 55

ible, they are only partially so and are lined with a more durable shaft engaging part. As shown, the fibrous or felt part 30 surrounds an inner or liner part 31 which may be somewhat spherical and have firm support on the sloping or camming faces of the retainers 32 and 33. The outer retainer 33, in this embodiment of the invention, is combined with and forms a part of the end wall of the shaft chamber (part 8 of Fig. 1). The spherical parts 31 of the bearings may be formed of graphite, bronze or porous bronze, and the encircling felt parts 30 supplied with a quantity of oil for properly lubricating the composite bearing. The inner retainers are urged outwardly by the common spring 13 and will compress the oil containing felts as permitted by the parts 31.

As lateral motion of the shaft occurs, these spherical parts will yield laterally between their retainers. To facilitate this lateral floating movement of the shaft the inner retainers 32 are preferably of less diameter than the shaft chamber 1 so as to move readily with the spherical bearings. Obviously lateral play of the shaft 25 will tend to compress the oil containing parts 30, and while the part 31 of the composite compressible bearing 30, 31 is referred to as being spherical, this term is employed for ease of description and not by way of limitation, since other practical shapes may be given this part. This bearing not only permits lateral movement of the shaft but it is self-aligning for better performance in operation and for greater ease in manufacture. The parts 30 and 31 may be integrally united, if desired, although for practical reasons this is not necessary, and for ease in description the composite bearing is referred to as a bearing block or felt.

For greatest efficiency and to avoid unnecessary drain on the vehicle power plant, it is desired to operate the rotor by fluid pressure rather than electricity or mechanically, and as a convenient means for obtaining the required pressure differential the housing 1 may be connected through the port 15 to a source of suction or negative pressure, such as the intake manifold motor of the vehicle engine (not shown). The source of suction when open to the housing 1, will place the rotor chamber 16 under a pressure below atmospheric and thus induce an inflow of air from the outside through a jet orifice 18 and against the blades 17 of the rotor 2.

For safety, the propeller 4 may be enclosed in a cage 22, which is supported by a ring 23 that has threaded engagement with the housing 1, as indicated in Fig. 1. This mounting ring may have a lip 24 overhanging the end wall 8 and enclosing the sealing valve to limit its lateral play. Likewise, the inturned lip 14 will 60 coact with a spacing disc 25 on the rotor end of the shaft 3 in restricting lateral play and against the shaft directly contacting the housing.

To avoid premature depletion of the lubricant supply from the bearing felts 10 by reason of air seepage through the latter, air ducts or passages 19 are provided to by-pass the air about the bearings, so that any leakage of air around the shaft and through the opening 9 will have no 70 extracting effect on the oil in the felts.

To further insure longevity to these bearings, means are provided to practically close the opening 9 to passage of air therethrough. Accordingly, a sealing valve 26 in the form of a disc of leather or some other good sealing material is

placed over the shaft between the hub 5 and the outer face of the end wall 8 for sealing the opening 9, the end wall serving as a seat for the valving leather disc. This sealing valve permits rotation of the shaft therein but moves laterally therewith and, therefore, it functions as a damper to any chattering tendency of the shaft. 5

If the rotating unit is unbalanced, or becomes unbalanced during operation through mechanical imperfection or through any reactionary effort of the propeller, so that the shaft tends to shift laterally in the opening 9, the sealing valve will likewise slide on its seat face of the wall 8 but nevertheless maintain a practical seal against the entrance of air. Since the under side of the valve is subjected to the low pressure maintaining in the rotor chamber, the outside atmosphere will serve to create a pressure differential and thereby hold the valve firmly on its seat. Because of this fluid pressure differential the valve 20 will have a steady influence on the shaft and frictionally brake or counteract any chattering tendency of the shaft against the wall of opening 9. The pressure differential acting on the sealing valve is supplemented by the reaction of the 25 propeller 4, the hub 5 of which exerts a sealing pressure on the valve axially of the shaft. A wearing disc 21 of a relatively hard substance is superimposed upon the valve, and the hub 5 may be reduced in diameter for seating on the 30 wearing disc to reduce the friction in the rotary engagement therewith. Should the shaft shift laterally in its floating mounting the friction of the valve on its seat, as provided by the fluid pressure differential, will retard rebound and thereby effectively dampen the tendency toward vibration. 35

The operation of the improved fan will be obvious from the foregoing. When the fan motor is started operating, the propeller will turn 40 as a unit with the shaft and the driver 2. If through some unbalanced part, whether it be due to mechanical or operative reasons, the shaft moves laterally in its bearing, such shifting movement will be retarded by the sealing valve. Chattering noise will, therefore, be avoided and the fan rendered quiet in operation. Any air leaking through the chamber 1 will not pass through the bearing felts to withdraw the lubricant therefrom (the term felt being used herein as inclusive of like suitable materials for supporting the shaft in a self-adjusting manner), the air in its travel from opening 9 passing outwardly through the radial extensions 19 of the by-pass 19. 50

The floating or yielding lateral motion of the 55 shaft, set up through vibration thereof, is effectively resisted by the braking action of the sealing valve, the latter being actuated as a brake by the fluid power supplied the fan motor. This insures a quiet operation for the fan. 60

It will be understood that the structure herein disclosed is merely illustrative of the inventive principles involved, which may be applied to other physical embodiments without departing from the scope and spirit of the invention 65 claimed.

What is claimed is:

1. A housing provided with a shaft chamber and a fluid chamber adapted to be connected to a source of suction, a drive member in the fluid chamber, a shaft connected to the drive member and extending through the shaft chamber for supporting a propeller on the protruding end of the shaft member, and a lubricant-containing bearing block disposed within the shaft cham- 75

- ber and constituting the sole support for the shaft, the housing being otherwise spaced from the shaft and provided with a fluid passage bypassing the bearing block in the shaft chamber whereby to forestall the extraction of lubricant from the bearing block by reason of fluid leakage along the shaft into the fluid chamber.
2. A motor having a housing provided with a rotor chamber and a shaft chamber, a rotor disposed in the rotor chamber, a shaft in the shaft chamber and supporting the rotor, said rotor chamber having a passage for communication with a source of operating pressure for rotor operation, a porous lubricant holding bearing block in the shaft chamber supporting the shaft out of contact with the housing, means yieldably retaining the block in position, and an air passage establishing communication between portions of the housing at opposite sides of and about said bearing block to by-pass leakage fluid through the shaft chamber.
3. A fan motor having a housing provided with a rotor chamber and a shaft chamber, a rotor disposed in the rotor chamber, a shaft extending through the shaft chamber and supporting the rotor, a porous bearing block disposed within the shaft chamber and yieldably supporting the shaft, an air passage establishing communication between portions of the housing at opposite sides of and about said block, the housing being provided with a valve seat about the outer end of the shaft, and a valve sealing the clearance between the shaft and the housing against air passage along the shaft into the shaft chamber and serving to restrain lateral motion of the shaft.
4. A fan motor having a housing provided with a rotor chamber and a shaft chamber, a rotor in the rotor chamber, a shaft extending through the shaft chamber and supporting the rotor, said rotor chamber having fluid communication for rotor operation, a bearing block having a fibrous lubricant holding part disposed within the shaft chamber in contact with the shaft, an air bypass about the fibrous part, the housing being provided with a valve seat about the outer end of the shaft, and a valve closing the clearance between the shaft and the housing against air passage along the shaft, said shaft adapted for limited axial movement during operation and having a part for bearing on the valve to urge it to its seat during such movement.
5. A motor having a housing provided with a motor chamber, a driver in the chamber, said housing having a shaft chamber, a shaft extending through the shaft chamber and supporting the driver on its inner end, the outer end of the shaft extending from the housing, spaced lubricant holding bearing blocks within the shaft chamber having engagement with the shaft, a retainer member for each block slidably in the shaft chamber and serving to confine the bearing blocks in position, resilient means interposed between the retaining members to hold the blocks in a normal shaft supporting position, said housing having a passage leading from the motor chamber about the bearing blocks for by-passing any air which may enter the shaft chamber along the shaft, and a sealing valve for sealing the clearance between the housing and the shaft at its outer end.
6. A fluid pressure motor having a housing with a motor chamber and a shaft bearing chamber, said chamber having a passage for connection to a source of operating pressure, a porous shaft bearing disposed in the shaft bearing chamber and having a contained lubricant, a shaft journalled in the bearing, means in the motor chamber connected to the shaft and operable by fluid pressure for driving the shaft, and means communicating with the motor chamber at one side of the bearing and with the shaft at the opposite side of the bearing for by-passing leakage fluid about said bearing to equalize the pressure on opposite sides of said bearing and thereby preclude fluid exhaustion of the contained lubricant.
7. A fan motor comprising a housing having a drive chamber, a rotary shaft, means yieldably supporting the shaft in the housing to accommodate lateral vibration thereof incidental to rotation, a fluid pressure actuated means operable in the drive chamber and connected to the shaft for rotating the same, and means acting on the shaft and responsive to the fluid pressure supplied to said shaft rotating means for braking any vibrational motion of the shaft.
8. In combination, a housing provided with a shaft chamber and an adjacent fluid chamber in which the fluid pressure is different from the outside atmosphere, said fluid chamber having a passage for connection to a source of operating pressure, a shaft extending through the shaft chamber into the fluid chamber, fluid pressure operated means in the fluid chamber connected to the shaft for operating the same, and a lubricant-containing bearing block disposed within the shaft chamber and constituting the sole support for the shaft, the housing being otherwise spaced from the shaft and provided with a fluid passage communicating with the fluid chamber and by-passing the bearing block in the shaft chamber whereby fluid leakage along the shaft will be directed away from the block to forestall the extraction of lubricant therefrom.
9. A bearing for a rotating shaft of a pressure operated motor, comprising a chamber in communication with a source of operating pressure at one side and open to the atmosphere at the opposite side, a shaft, a porous lubricant holding bearing block in the shaft chamber supporting the shaft out of contact with the housing, means yieldably retaining the block in position, and an air passage establishing communication between portions of the housing at opposite sides of and about said bearing block to by-pass leakage fluid through the shaft chamber around the block.
10. A bearing for a rotating shaft of a pressure operated motor, comprising a chamber, a shaft, a porous bearing block disposed within the shaft chamber and yieldably supporting the shaft out of direct bearing contact with the chamber, an air passage establishing communication between portions of the chamber at opposite sides of and about said block, the chamber being provided with a valve seat about the outer end of the shaft, and a valve sealing the clearance between the shaft and the chamber against air passage along the shaft and serving to restrain lateral motion of the shaft.
11. A bearing for a rotating shaft of a pressure operated motor, comprising a chamber, a shaft, a bearing block having a fibrous lubricant holding part disposed within the chamber in contact with the shaft, an air bypass about the fibrous part, the chamber being provided with a valve seat about the outer end of the shaft, and a valve closing the clearance between the shaft and the chamber against air passage along the shaft and serving to restrain lateral motion of the shaft.

the shaft, said shaft adapted for limited axial movement during operation and having a part for bearing on the valve to urge it to its seat during such movement.

5. 12. A fan comprising a housing having a drive chamber, a rotary shaft, means yieldably supporting the shaft in the housing to accommodate lateral vibration thereof incidental to rotation, a fluid pressure actuated means operable 10 in the drive chamber and connected to the inner end of the shaft for rotating the same, a propeller on the opposite end of the shaft, and means responsive to the fluid pressure supplied to said shaft rotating means for braking any vibrational 15 motion of the shaft.

13. In a fan accessory construction for motor vehicles, a housing provided with a motor chamber and a shaft chamber, a rotary shaft in the 20 shaft chamber, a drive member in the motor chamber fixed to one end of the shaft, a propeller fixed on the opposite end of the shaft, said propeller and drive member rotating with the shaft as a unit, and a laterally yieldable bearing member in the shaft chamber closely engaging the 25 shaft and supporting the unit out of contact with the housing, said bearing providing the sole means of support for the unit in the housing whereby the unit will be cushioned during rotation thereof against contact with the walls of 30 the shaft chamber due to any off balanced condition in the unit.

14. In a fan accessory construction for motor vehicles, a housing provided with a motor chamber and a shaft chamber, a rotary shaft in the 35 shaft chamber, a drive member in the motor

chamber fixed to one end of the shaft, a propeller fixed on the opposite end of the shaft, said propeller and drive member rotating with the shaft as a unit, a laterally yieldable bearing member in the shaft chamber closely engaging 5 the shaft and supporting the unit out of contact with the housing, said bearing member providing the sole means of support for the unit in the housing whereby the unit will be cushioned during rotation thereof against contact with the 10 walls of the shaft chamber due to any off balanced condition in the unit, and means acting on the bearing member to provide for self-adjustment of the same in the housing.

15. A fan having a shaft with a propeller on 15 one end and a rotor on the opposite end, a chamber in which the rotor operates and through one wall of which the shaft projects, a yieldable bearing for the shaft permitting lateral vibration of the latter during operation, and means acting 20 on the shaft and operable from the source of power for the rotor for braking any vibratory motion of the shaft.

16. A fan having a shaft with a propeller on one end and a rotor on the opposite end, a chamber 25 in which the rotor operates and through one wall of which the shaft projects, a yieldable bearing for the shaft permitting lateral vibration of the latter during operation, means for frictionally resisting the lateral vibration of the 30 shaft, and means acting through the resisting means for positively limiting the lateral movement of the shaft against chattering contact with the chamber wall.
